UNITED STATES PATENT OFFICE

2,474,187

CONTROL SYSTEM FOR FLUID MOTORS

Albert M. Olson, Wauwatosa, Wis., assignor to
 Chain Belt Company, Milwaukee, Wis., a corporation of Wisconsin

Application November 2, 1945, Serial No. 626,290

4 Claims. (Cl. 60—97)

1

The invention relates to control systems for fluid motors, and has for one of its objects the provision of an improved system for the actuation and control of a plurality of hydraulic or similar motors which are to be operated in timed relation to one another.

Various kinds of machines include two or more instrumentalities which are to be actuated in timed relation to one another, which instrumentalities are of a character whereby motors of the reciprocating piston hydraulic type may be advantageously employed. As an illustrative example of this class of machine, reference may be made to the apparatus for processing canned products disclosed in prior U. S. Patent No. 2,348,440 granted May 9, 1944, on an application filed by Horace L. Smith, Jr., and Weld E. Conley, Jr. While as will appear more fully below, the present invention is by no means limited thereto, yet for purposes of disclosure its application to the can feeding and can transfer mechanisms of such a machine has been selected for illustration here as affording a typical example of its use.

Briefly, the apparatus of the said patent comprises a series of power driven rolls disposed in spaced parallel relation in a tank or vat containing a flowing heat exchange medium such as water, which rolls receive columns of axially aligned cans in the valleys between them, for rotation while at least partially submerged in the heat exchange medium. At determined intervals oscillating transfer members effect synchronized advance of the several lines of cans to the next succeeding valleys, whereby the cans are progressively moved through the machine to a conveyer or other appropriate discharge device. Simultaneously with each advance of the lines of cans within the machine, a fresh batch of cans is supplied to the first valley of the roll series, the feeding mechanism including a conveyer and an intermittently operable can gripping device associated therewith for temporarily arresting movement of a portion of the line of cans on the conveyer after a determined number of cans has approached position for transfer to the roll series.

While in the said patent the can gripping device and the oscillating can transfer members are shown as being operated by electrical means, each of them may be advantageously operated

5 by a reciprocating fluid motor, and the present drawings illustrate a system and mechanism whereby such motors may be actuated and controlled to function in properly timed relation to one another to maintain the processing apparatus filled to its capacity.

10 On the forward or working stroke of the can transfer bars to effect advance of the cans from valley to valley, each of the said bars must raise its line of cans against the action of gravity to move them over the adjacent roll, and therefore the power supplied by the motor for this stroke must be sufficient to lift quite a number of filled cans. However, when the cans have been shifted over into the succeeding valleys the transfer members are relieved of the weight of the cans, and as the members travel more or less in a downward direction on their return strokes, such strokes may be effected with materially less pressure in the motor than is necessary for the working strokes. It is therefore a further object of the invention to provide a system whereby at least one of the motors may be operated at one pressure on one of its strokes and at a different pressure on the other stroke.

15 The can gripping mechanism may be and preferably is operated at a pressure lower than that necessary to effect the working strokes of the can transfer mechanism, in view of which the present system provides for supplying fluid to the circuit of the can gripper motor from the lower pressure portion of the transfer motor circuit.

20 Other objects and advantages of the invention will appear as the description proceeds.

25 In the accompanying drawings forming a part of this specification:

Figure 1 is a side elevational view, partly diagrammatic, of a processing machine of the type disclosed in the said prior Patent No. 2,348,440, illustrating the application of one form of the present hydraulic system to the can gripping and can transfer mechanisms of one deck of such machine;

30 Figs. 2, 3 and 4 are diagrammatic views of the system and mechanism, showing successive phases in the operation of the same;

35 Fig. 5 is a plan view of the timing mechanism for actuating the control valves of the two motor circuits, the housing therefor being shown in section; and

Fig. 6 is a side elevational view of the said timing mechanism, looking from the right of Fig. 5.

Referring to the said drawings more in detail, the processing apparatus shown in Fig. 1 comprises a vat or tank 10 which contains the heat exchange medium, and in which is mounted the series of can-supporting rolls and the oscillatory transfer bars mentioned above. The latter are intermittently operable from a rock shaft 11 through linkage 12, the said shaft being provided with an actuating arm 13 operable by a double acting fluid motor comprising a cylinder 14 having a piston 15 reciprocatable therein, and a piston rod 16 connected at 17 with said arm 13. Fluid under pressure is alternately supplied to and exhausted from the respective ends of the cylinder 14 through pipes 18 and 19 leading from control mechanism disposed within a cabinet or housing 20 adjacent the machine.

The cans are supplied to the roll series by feeding mechanism located at the left hand end of the tank 10 (as viewed in Fig. 1) which mechanism has associated with it the intermittent can gripping mechanism referred to above, and here diagrammatically indicated at 21. This device is operable by a double acting fluid motor comprising a cylinder 22 having a piston 23 reciprocatable therein, and a piston rod 24 which is appropriately connected to the can gripping jaws; and fluid under pressure is alternately supplied to and exhausted from the respective ends of the cylinder 22 through pipes 25 and 26 leading from the control mechanism in housing 20.

Referring now more particularly to Figs. 5 and 6, the mechanism contained in the housing 20 comprises a control valve 31 to which the pipes 18 and 19 leading from the motor 14 are connected, and a control valve 32 to which the pipes 25 and 26 leading from the motor 22 are connected. Each of these valves has an actuating rod or stem 33 engageable by a follower arm 34, which arms are respectively operable by rotatable cams 35 and 36 carried by a cam shaft 37 which is driven by a motor 39 through a reducing gear train 38. The cam 36 is here shown as being of an adjustable type having two segments 40 and 41 which may be adjusted arcuately relative to one another whereby to increase or decrease the length of the cam dwell and thus vary the length and/or timing of the gripping action as circumstances may require. The cam 35 of course may be of like construction, but for the purposes of the present apparatus a disc provided with an integral or rigid toe 42 will suffice.

As is best shown in Figs. 2, 3 and 4, the valve 31 is provided with an inlet port 45, a pair of exhaust ports 46 and 47, and a pair of motor ports 48 and 49, to the latter of which the pipes 18 and 19 are respectively connected. These several valve ports are controlled by a reciprocatable spool 50, which is movable in one direction by the cam actuated stem 33, and in the opposite direction by fluid under pressure admitted to a chamber 51 in the valve casing, as will appear more fully below. Fluid is supplied to the inlet port 45 through a pipe 52 leading from a gear pump 53 which draws its supply from a sump or reservoir 54 through a pipe 55. A branch 56 of the pipe 52 contains a relief or safety valve 57 which drains back to the sump 54 through a pipe 58, and which is set to relieve pressure in the line should it exceed, for example, 600 lbs. per sq. in.

The exhaust ports 46 and 47 of the valve 31

are connected by pipes 59 and 60 with the sump or reservoir 54; and a branch 61 of pipe 18 contains a relief valve 62 which drains through a pipe 63 to the said sump, and which valve is set to maintain a pressure of say not in excess of 125 lbs. per sq. in. in the line 18. A branch 65 of the pipe 56 is adapted to supply fluid at the higher, e. g. 600 lb., pressure to a pilot valve 66 which is disposed for actuation, either directly or indirectly, by the motor 14 through lost motion connections 67. In one position of this pilot valve (shown in Figs. 2 and 3) the supply line 65 is blocked off by the valve, while in another position of the said valve (shown in Fig. 4) its supply line 65 is connected to a pipe 69 leading to the chamber 51 of the control valve 31. A relief line 70 connects the pipe 69 to the pipe 18, said relief line containing a relief valve 71 which may be set to limit the pressure exerted on the spindle 50 to say 15 lbs. per sq. in. when the pilot valve 66 opens communication between lines 65 and 69.

The control valve 32 for the motor 22 has an inlet port 75, a pair of exhaust ports 76 and 77, and a pair of motor ports 78 and 79, to which latter the pipes 25 and 26 are respectively connected. The inlet port 75 is supplied with fluid under say 125 lbs. pressure through a pipe 80 leading from the pipe 18 and containing a check valve 81; and the exhaust ports 76 and 77 of the motor control valve are connected by pipes 82 and 83 with the sump or reservoir 54. The several valve ports are controlled by a reciprocatable valve spool 84 movable in one direction by the cam actuated stem 33 and in the opposite direction by a compression spring 85.

In Fig. 2 the various parts are shown in the positions they occupy throughout a major portion of a cycle of the apparatus, during which the can gripping mechanism is operative to prevent cans from moving into tank 10, and the can transfer bars are in inoperative position below the several valleys of the roll series. At this time the pump 53 (which operates continuously) is supplying fluid at say 600 lbs. pressure through pipe 52 to the inlet port 45 of valve 31, and the valve spool 50 has placed this port in communication with the motor port 48 so that fluid pressure is being exerted upon the top of piston 15 through the pipe 18, as indicated by the arrows. However, the relief valve 62 which is in communication with pipe 18 by the connection 61 is reducing the pressure in pipe 18 to say 125 lbs. per sq. in. so that fluid reaching the upper part of motor cylinder 14 is under such reduced pressure. The valve spool 50 has also placed the exhaust port 46 in communication with the motor port 49 so that the line 49 leading from the lower portion of motor cylinder 14 is connected with exhaust line 59 leading to the sump 54. The motor piston 15 will thus be maintained in the lower position shown in Fig. 2.

Should the pressure of the fluid in pipes 52 and 56 tend to exceed 600 lbs. per sq. in., the valve 57 will relieve such excess, venting the fluid to the sump through pipe 58.

In the meantime, fluid from pipe 18, at 125 lbs. pressure, is passing through pipe 80 and check valve 81 to the inlet port 75 of valve 32 which controls the motor 22 of the can gripping mechanism 21. The spool 84 of this valve has placed the said inlet port in communication with the motor port 79, and the valve exhaust port 76 in communication with the motor port 78. Pressure is thus being exerted through pipe 26 upon the

lower face of motor piston 23 to maintain such piston in its upper or gripping position.

The valve actuating cams 35 and 36 are being continuously rotated by motor 39, and at the proper time in the cycle, the segments 40, 41 of the cam 36 move the follower 34 of valve 31 to shift the valve spool 84, against the action of spring 85, to the Fig. 3 position. This places the inlet port 75 in communication with the motor port 78, and the valve exhaust port 77 in communication with the motor port 79 and causes fluid pressure to be exerted on the upper face of motor piston 23 through pipe 25, whereby said piston will be moved to its lower position and thus move the gripping jaws of the mechanism 21 to can-releasing position. As piston 23 moves downwardly, fluid in the lower portion of motor cylinder 22 is exhausted to sump 54 through pipe 26, valve ports 79 and 77, and pipes 83 and 82.

During this phase of the cycle the elements of the can transfer circuit have maintained the positions above described in connection with Fig. 2, since the toe 42 of cam 35 has not yet actuated the follower 34 of valve 31 to shift the valve spool 50. As the transfer of the fresh batch of cans to the roll series is completed, the segments 40, 41 of cam 36 move out of engagement with follower 34, permitting spring 85 to return valve spool 84 to the position of Figs. 2 and 4, whereby fluid pressure will again be admitted to the lower portion of motor cylinder 22 through pipe 26, and exhausted from the upper portion of such cylinder through pipe 25, returning the piston 23 to its upper position whereby the mechanism 21 will cause one of the cans to be gripped and thus arrest further movements of the row of cans on the feeding conveyer.

The relief valve 62 is selected or set to secure sufficient pressure in back of it so that at the moment the spool 84 is shifted to either of its positions, the piston 23 will be moved rapidly and quick action of the gripping mechanism will be effected. The pressure is not so great, however, as to cause damage to the cans when they are gripped, such as might occur if the full pressure from the pump were utilized and the relief valve were not employed. The relief valve also permits the pump to circulate fluid through the circuit at a lower pressure during that portion of the cycle when the fluid motors are inoperative.

At a very short interval of time subsequent to the return of the elements of the can gripper circuit to their gripping positions, the toe 42 of cam 35 will actuate the follower 34 of valve 31 to shift the valve spool 50 to the position shown in Fig. 4. This will bring the valve inlet port 45 into communication with the motor port 49, and the valve exhaust port 47 into communication with the motor port 48, whereby fluid may pass through pipe 19 to the lower portion of motor cylinder 14, while fluid from the upper portion of such cylinder escapes through pipe 18, valve ports 43 and 47, and pipes 60 and 59 to the sump 54. This causes motor piston 15 to move upwardly to its Fig. 4 position and through arm 13 to move rock shaft 11 and linkage 12, whereby to cause the transfer bars of the processing apparatus to make a working stroke which moves a batch of cans from the conveyer into the roll series and also advances the several lines of cans in the roll series from valley to valley thereof. The full pressure of the pump is available at this time to lift the filled cans over the rolls.

During the first portion of this movement of

the piston 15 the position of the pilot valve 66 is not changed, due to the lost motion connections 67, but as the piston approaches its upper position such connections pick up and shift the pilot valve to its Fig. 4 position, whereby as the toe 42 of cam 35 disengages follower 34, such pilot valve will place the pipes 65 and 69 in communication. Fluid will thus be supplied to the chamber 51 of the motor control valve 31 and will restore the valve spool 50 to its initial position. The pressure in the lower part of line 69, effective for moving the valve spool 50 in this operation, is reduced by the valve 71 as above explained, the excess fluid passing to the line 18, which at this time is in communication with the sump 54 through valve ports 48 and 47. The restoration of the pilot valve 66 to its initial position is accomplished through the lost motion connections 67 toward the end of the return stroke of the motor piston 15, which takes place upon the return of the valve spool 50 to its Fig. 2 position, whereby the line 66 is again placed in communication with the fluid supply from pump 53, and fluid is passed through such line to the upper portion of the cylinder 14.

This brings all parts back to the Fig. 2 positions and completes the cycle, which will be repeated with each revolution of the cams 35 and 36.

When the pilot valve 66 is in the position shown in Figs. 2 and 3, supply of fluid from line 65 to line 69 is cut off, and since the latter line is at this time in communication with the return line 68, there will be no pressure in the chamber 51 of control valve 31 tending to hold its valve spool 50 in the Fig. 2 position. While the fluid pressures within valve 31 are substantially balanced as regards their action upon its said spool, and while friction between the parts may serve to retain the spool in this position until positively moved by cam 35, to guard against any unintentional displacement of the spool prior to such cam action, a spring actuated detent 86 may be associated with the valve rod 33, as indicated in Fig. 6.

By reason of the connection 70 between the lines 69 and 18, and the provision of the relief valve 71 therein, when the spool 50 is first shifted from the Fig. 4 position back to the Fig. 2 position (and before the lost motion connections 67 have shifted the pilot valve 66 back to its Fig. 2 position) the build-up in pressure in line 18 from supply line 52 will be accelerated by the fluid which is escaping from the line 69 through valve 71, and the return of the piston 15 to its Fig. 2 position will thus be hastened. If the line 69 were vented directly to the sump or to the return line 68, this accelerated build-up of pressure in line 18 would be lost, with consequent retardation of the return stroke of the piston 15.

The pressure thus built up in line 18 (which can never exceed that for which relief valve 62 is set) will also tend to cut down the fluid escaping from line 69 through valve 71, thereby causing an increase in the pressure being supplied to the valve chamber 51 by the line 69. As a result, during the relatively short time between the respective movements of the spool 50 and the pilot valve 66 back to their Fig. 2 positions, the pressure in chamber 51 acting on the spool 50 will increase above the 15 lbs. per sq. in. which existed in the said chamber when fluid from the line 69 was passing through the lines 18, 60 and 59 to the sump; and such increase may continue

until the pressure in chamber 51 equals that of the lower pressure side of the circuit. This increased pressure cannot be created until the spool 50 is returned and hence there is no danger of the cam follower putting undue pressure on the cam shaft prior to the passing of the toe 42 from engagement with the follower; but the moment the toe has passed the follower and the port 48 has been put into communication with the port 45, the pressure on the spool and its associated cam follower will build up until the pilot valve 66 is shifted to cut off supply of fluid to the line 69. Of course, no pressure can pass from the line 18 to the line 69 because the valve 71 checks all flow in this direction.

It will be noted that when the parts are in the Fig. 4 positions the line 18 of the transfer circuit (which normally supplies the fluid for the gripper circuit) is cut off from the supply line 52 leading from the pump, and is in communication with the sump 54 through exhaust pipes 60 and 59. At such time the pressure in line 18 will fall below the 125 lbs. per sq. in. normally maintained therein by the relief valve 82, which will tend to drain fluid from the gripper circuit. However, the check valve 81 which is included in the feed line 80 of the gripper circuit will prevent any appreciable loss of pressure in this circuit while it is thus cut off from its source of supply, and thereby prevent possible undesired movements of the gripping jaws which might interfere with proper feeding of the cans.

What is claimed is:

1. In a control system for a reciprocating fluid motor, a fluid circuit for said motor; means for establishing differential fluid pressures in different portions of said circuit; a valve controlling said circuit, movable between positions in which it successively connects the motor in the circuit for alternate movement of its working element in opposite directions at different pressures; connections between a higher pressure portion of said circuit and said control valve for supplying motive fluid to the latter; a pilot valve controlling said connections, operable by the motor as its working element approaches each terminus of movement to alternately supply and cut off motive fluid to said control valve to effect movement of the latter to one of its positions; means for reducing the effective pressure of the motive fluid supplied to said control valve to move the same, and for securing a rapid build-up of pressure in the lower pressure portions of the fluid circuit to cause quick actuation of the motor element after the control valve has completed its movement, comprising relief connections between said motive fluid supply connections and the lower pressure portion of the circuit; and additional means for moving the control valve to its other position.

2. In a control system for a reciprocating fluid motor, a fluid circuit for said motor; means for establishing differential fluid pressures in different portions of said circuits; a valve controlling said circuit, movable between two positions, in one of which it supplies fluid from a lower pressure portion of the circuit to one side of the working element of the motor to effect movement of said element in one direction, said valve in the other of its said positions supplying fluid from a higher pressure portion of the circuit to the other side of said motor element while exhausting fluid from the first mentioned side thereof through said lower pressure portion of the circuit, whereby to cause movement of said

element in the opposite direction; means for moving said valve from its first mentioned to its second mentioned position; connections between a higher pressure portion of the circuit and said control valve for supplying motive fluid to the latter to move it back to its first mentioned position; a pilot valve controlling said motive fluid supply connections; means for actuating said pilot valve whereby to supply motive fluid to the control valve when the latter is in its second mentioned position; connections between said motive fluid supply connections and the lower pressure portion of the fluid circuit for venting part of the high pressure fluid from said supply connections to said lower pressure circuit portion, whereby to reduce the fluid pressure effective for moving the control valve and effect a rapid build-up of pressure in said lower pressure circuit portion when the control valve completes its movement; and a valve controlling said pressure reducing connections.

3. In a control system for a reciprocating fluid motor, a fluid circuit having portions connected to the motor for alternate supply and exhaust of fluid to and from each side of the working element thereof; means for establishing differential fluid pressures in the respective circuit portions; a control valve in said circuit, movable between positions in which it effects alternate supply of fluid from said differential pressure portions of the circuit to said working element to move the latter in opposite directions at different pressures; connections between the higher pressure portion of the circuit and said control valve for supplying motive fluid to actuate the latter in one direction; means for moving said valve in the other direction; a pilot valve in said motive fluid supply connections; means for actuating said pilot valve to supply motive fluid to the control valve while the lower pressure portion of the circuit is exhausting fluid from the motor; relief connections between the motive fluid supply connections and said lower pressure portion of the circuit, for venting fluid from said supply connections to said lower pressure circuit portion, whereby to effect a rapid pressure build-up in the latter when the control valve completes its fluid pressure induced movement; and a combined relief and check valve in said relief connections for securing a lowered fluid pressure in a portion of said motive fluid supply connections for moving said control valve, said relief and check valve also acting to prevent reverse flow of fluid from the lower pressure portion of the motor circuit to said supply connections for the valve motive fluid when the pilot valve cuts off supply of fluid to the latter connections.

4. In a control system for a pair of intermittently operable fluid motors deriving their power from a single source, a fluid circuit for one of the motors; means for establishing differential fluid pressures in different portions of said circuit; a second fluid circuit, for the other of said motors, connected to and receiving its supply of fluid from one of the differential pressure portions of the first circuit; a valve in each of said circuits for supplying fluid therein to its motor to reciprocate the working elements thereof, the valve in the first circuit connecting the motor therein to one pressure portion during the forward stroke of its working element and to the other pressure portion during the return stroke of said element; means for actuating the valve in the first circuit in one direction by pressure from said first circuit; additional means for

actuating said valve in the opposite direction; means for actuating the valve in the second circuit; and means for co-ordinating the action of the two last mentioned means.
